[57] CLAIM

The ornamental design for a tape guide roller, as shown and described.

DESCRIPTION

FIG. 1 is a perspective view of a tape guide roller, showing my new design;

FIG. 2 is a front elevational view thereof, the rear being a mirror image;

FIG. 3 is a right-side elevational view thereof, the left-side being a mirror image;

FIG. 4 is a top plan view thereof, the bottom being a mirror image; and,

FIG. 5 is a cross-section elevational view thereof taken along line 5—5 of FIG. 4.

The broken line showing of the tape and spindle in FIG. 1 is for illustrative purposes only and forms no part of the claimed design.

FIG. 2

FIG. 3

FIG. 4

FIG. 5
